UNITED STATES PATENT OFFICE.

THOMAS R. BUTMAN, OF CLEVELAND, OHIO.

STEAM-BOILER SETTING AND FURNACE.

SPECIFICATION forming part of Letters Patent No. 279,331, dated June 12, 1883.

Application filed October 26, 1882. (No model.)

To all whom it may concern:

Be it known that I, THOMAS REED BUTMAN, of Cleveland, in the county of Cuyahoga and State of Ohio, have invented certain new and useful Improvements in Steam-Boiler Settings and Furnaces; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to the settings of steam-boilers and to steam-boiler furnaces, and is an improvement in that kind of furnace in which an arch is sprung over the boiler, and in which air is heated and fed into the fire-box for producing complete combustion of the fuel and the gaseous products thereof, whereby the heat is utilized and the full calorific value of the fuel is more nearly realized in effective work.

The object of the invention is to more uniformly and safely heat the boiler, thereby preventing injurious strain upon it, to utilize waste heat and produce complete combustion, and to construct a yielding double wall which shall be free from strain and breakage due to expansion and contraction under the influence of heat and subsequent cooling.

It is a well-known fact that with the ordinary steam-boiler settings the heat is unevenly distributed to the water-surfaces of the boiler, thereby producing unequal expansion and consequent severe strain upon the boiler and brick-work; also, that a large amount of heat is lost through the side walls and from the upper portion of the boiler by radiation. Now, by my improved construction I overcome these serious defects. In my system of boiler-setting the side walls are constructed with air-spaces, and an arch is sprung over the boiler, the walls being brought into contact with the boiler only circumferentially at the ends thereof, and pendent brick partitions are arranged in the arch at a suitable distance apart, extending down between the wall of the arch and the boiler to about the water-line on each side. They prevent the flame extending above the water-line of the boiler, but allow of the steam-space being jacketed with stagnant hot gases,

effectually preventing radiation and slightly superheating the steam, thereby greatly increasing the capacity and durability of the boiler. Another important feature is the shape or contour of the side walls of the furnace with relation to the boiler. I construct the side walls so that the space between them and the boiler shall be greater forward of the bridge-wall, at or near which I cause them to converge, gradually reducing the space between them and the boiler. This allows of more expansion of the flame and gases at the forward part of the furnace, where the heat would usually be the greatest, and causes the flame and gases to press closer and closer as they flow back against the sides or shell of the boiler, thereby intensifying the heating effect at the rear as compared with the heat usually brought to bear at the rear portions, resulting in the more uniform distribution of the heat to all portions of the boiler.

In furnaces with double walls as ordinarily constructed the inner wall becomes more highly heated and consequently expands more than the outer wall, and, the two being tied together, the inner wall, when heated, raises the tie-brick and causes the outer wall to crack. To overcome this and cause the outer wall to support the inner wall, I extend brick from either the outer or inner wall across the intervening space, allowing them to abut against the opposite wall, but not tied to the same. By so doing I make a slip-joint, which allows either wall to expand or contract without disturbing the other. I jacket the smoke-flue of metal with a suitable material, providing an air-space between the flue and jacket having an opening at one or more places for the admission of air, and connect said air-space to the chambers or spaces in the furnace-walls, whereby the air may be drawn down through the space in the jacket, thence through connecting-pipes and spaces in the walls, and admitted to the fire-box and combustion-chamber of the furnace by any of the well-known means, supplying the hot gases with hot air for producing complete combustion. I place an injector or steam-blower in the combustion-chamber, connecting by pipes at the suction end with the air-spaces in side walls, and discharging into the calorific box or partition-wall in the fire-box for drawing the air through the space

between the smoke-flue and its jacket and the spaces in the side walls and discharging it into the fire-box above the fuel.

Having set forth the nature and object of my 5 invention, I will now proceed to describe it more particularly with reference to the accompanying drawings, which form part of this specification, in which—

Figure 1 is a transverse vertical section of 10 the boiler and furnace, showing the double side walls, the arch over the boiler, the calorific box or partition-wall in the fire-box, and the smoke-flue and jacket in elevation. Fig. 2 is a longitudinal vertical section of the furnace- 15 walls and arch, showing the smoke-flue and jacket in transverse section. Fig. 3 is a horizontal section of the furnace-walls below the boiler, showing the steam and air pipes in the bottom of the combustion-chamber. Fig. 4 is 20 a detached side view, on an enlarged scale, of the calorific box or air-feeder; and Fig. 5 is a cross-section thereof.

In the following description like letters refer to like parts in all the figures.

25 A represents the boiler, having connected with its front end the smoke-flue A', extending partially around which is the jacket B, providing an air-space, b, between it and the flue. Connected with this space are the pipes b', leading 30 to the air-spaces in the side walls of the furnace. The boiler is supported upon the front wall and upon the spool or roller c in the rear bridge-wall, C, the roller permitting free movement of the boiler upon its supporting-wall 35 during expansion and contraction. The side and rear walls are made double, being composed of the outer wall, D, and the inner wall, D', converging slightly from the front bridge-wall, E, to the rear, so as to contract the combustion-chamber toward the rear end of the 40 boiler, and cause the flame and gases to press more closely upon the shell of the boiler and uniformly distribute the heat from the front to the rear end of the boiler. The walls are 45 also so constructed as to provide an air space or chamber, d', extending from top to bottom in the sides and at the rear. These walls are not connected to each other by tie-brick, but are supported one by the other by means of 50 brick or headers secured in one wall and abutting loosely against the other wall, forming a slip-joint, whereby, during unequal expansion and contraction of the two walls, due to a difference of temperature and to changes therein, 55 all cracking and straining of the brick-work are prevented, and the walls are much more durably and effectively maintained. The lining G of the inner wall is curved, partially conforming to the boiler, for forming a suitable 60 combustion-chamber, and is carried in the form of an arch, H, over the top of the boiler, but not in contact with it, except at each end, it being brought close around the front end and the upper half of the rear end. Extending from this 65 arch, between it and the boiler, are the pendent partitions h, at suitable distances apart, and extending down to about the water-line of the

boiler, for forming spaces into which the flame does not circulate, but in which the hot gases are held in a comparatively stagnant condition for superheating the steam in the upper part of the boiler. An opening, I, in the outer rear wall admits air, when desired, in the space between the walls. It may be closed by a door when not in use. A deflector, i, secured to the inner wall, opposite the opening I, spreads the air to each side of the air-space. A transverse arch, K, closes the rear smoke-flue at the top. A transverse pipe, L, connects with the air-spaces in the side walls and centrally with the injector-pipe leading to the calorific box or air-feeder M, mounted on the division-wall F. A steam-pipe, N, is coiled in the combustion-chamber for superheating the steam, and connects with the injector-pipe L' 70 at the junction of the air-pipes therewith. By the jet of steam thus introduced into the injector air is drawn through the space between the smoke-flue and its jacket and through the space in the side walls, being heated on its way 75 by the escaping hot products of combustion 80 and by the heat that would usually be lost by radiation from the side walls, and is forced into the calorific box M, and thence through the slots or openings m into the fire-box on each 85 side of the division-wall for supporting combustion of the smoke and gases from the fuel. The steam being superheated in the coil is decomposed in the fire-box, resulting in carbonic 90 oxide and hydrogen, which are burned by the oxygen of the hot air admitted, and yield an intense heat. The hot steam and air are further heated in the calorific box, are forced 95 therefrom in horizontal jets into the rising gases, so as to be uniformly mingled therewith, and thus produce most perfect combustion 100 and prevent all escape of unconsumed carbon and combustible gas. The jacket of the smoke-flue may be provided with openings at the ends or at other convenient points for the 105 admission of air.

Having described my invention, I claim and desire to secure by Letters Patent—

1. In a furnace, the combination of the smoke-flue and its jacket with the air-chamber in the 115 walls of the furnace and the connecting-pipes, for the purpose described.

2. In combination with the jacketed smoke-flue, the double walls of the furnace, provided with an air space or chamber, the pipe connections between the jacket and air-chamber, and connecting-pipes between the lower part of the air-chamber and fire-box.

3. The double wall of the furnace, provided with an air space or chamber, and constructed 125 with headers or brick secured in one wall and abutting loosely against the opposite wall, whereby slip-joints are formed, and cracking and breaking of the brick-work by unequal expansion and contraction of the two walls are 130 prevented, in combination with a suitable air-inlet from the jacket of the smoke-stack, and a pipe or flue connecting the air-chamber with the fire-box of the furnace.

4. The combination of the injector L' and the calorific box M, provided with the lateral slits or openings, mounted on the division-wall, all being relatively arranged as described.
5. In combination with the air-heating chambers, the steam-jet injector-pipes connecting the air-chamber with the injector and the perforated calorific box, as described.
6. In a horizontal steam-boiler furnace, the converging side walls, as described, and an independent air-chamber, in combination with a steam-boiler and suitable supports therefor.
7. In a steam-boiler furnace having suitable side walls, the arched covering, in combination with the pendent partitions extending at intervals between the arch and the boiler, for the purpose described.
8. The side walls converging from near the front bridge-wall toward their rear end, in combination with the arched covering rising 20 slightly above the boiler and the pendent partitions, substantially as described.
- In testimony that I claim the foregoing as my own I affix my signature in presence of two witnesses.

THOMAS REED BUTMAN.
